DESIGN FOR A COMBINATION SPORT AND DRESS HAT

Fred Lacome, New York, N. Y.

Application December 3, 1941, Serial No. 104,448

Term of patent 3½ years

To all whom it may concern:

Be it known that I, Fred Lacome, a citizen of Belgium, and residing at New York, county and State of New York, have invented a new, original, and ornamental Design for a Combination Sport and Dress Hat, of which the following is a specification, reference being made to the accompanying drawing, forming a part thereof.

Fig. 1 is a perspective view as seen from the bottom of the hat showing my new design.

Fig. 2 is a perspective view as viewed from the top showing the hat parts in separated condition.

I claim:

The ornamental design for a combination sport and dress hat, substantially as shown.

FRED LACOME.
